EDWIN J. POOLE, OF CLEVELAND, OHIO

SAFETY STARTER SWITCH

Application filed November 17, 1930. Serial No. 496,251.

This invention relates to a safety starter switch for internal combustion engines, the general object of the invention being to provide means for preventing the starter switch from being closed until the ignition circuit is closed and to provide means for automatically rendering the device inactive when the engine starts.

10 This invention also consists in certain other features of construction and in the combination and arrangement of the several parts, to be hereinafter fully described, illustrated in the accompanying drawing and specifically pointed out in the appended claims.

15 In describing the invention in detail, reference will be had to the accompanying drawing wherein like characters denote like or corresponding parts throughout the several views, and in which:

20 Figure 1 is a sectional view through the invention.

Figure 2 is a section on line 2-2 of Figure 1.

25 Figure 3 is a detail view showing the switch on the timer.

Figure 4 is a sectional view through said switch.

30 In these views, the numeral 1 indicates a casing containing the switch parts 2 and 3 for closing the circuit of the starter motor, the part 3 being pressed against the part 2 when the starter button 4 is depressed.

35 In carrying out the invention, I provide a member 5 which is hinged at its lower end to the bottom of the casing, as shown at 6, with a spring 7 normally holding the top of the member under the member 3 so as to prevent said member 3 from being pushed by the button 4 into engagement with the member 2.

40 An armature 8 is carried by the member 5 and is adapted to be attracted by a pair of magnets 9 in the casing when the same are energized so that the member 5 will be swung from under the member 3 to permit said member 3 to be lowered into engagement with the member 2. One of the magnets is grounded, as shown at 10, and the other magnet is connected by a conductor 11 with a switch arm 12 in the casing, this arm being 45 normally in engagement with a contact 13

which is connected by a conductor 14 to the ignition switch so that when the switch is closed, current will pass through the conductor 14, through the contact 13 and arm 12 and through the magnets so that the member 5 will be swung from under the member 3 to permit the button 4 to be depressed and the starter motor circuit to be closed. It will be seen that the ignition switch must be closed 55 before the starter switch can be closed. After the engine starts up, a vacuum will be produced in a pipe 15 which extends into the casing and has its end located adjacent a conical member 16 on the switch member 12 so that the suction in the pipe 15 will draw the member 16 against the end of the pipe and thus move the switch member 12 out of engagement with the switch member 13 and thus break the circuit to the magnets. Thus the member 5 will be returned by the spring 7 60 under the starter switch member 3. If the engine should stop for any reason, the suction in pipe 15 will be broken so that the member 12 would again engage the member 13 and close the circuit to the magnets, provided the ignition switch is still closed so that the starter can be operated to again start the engine.

65 The pipe 15 is connected to the intake manifold of an engine so that the member 12 is 80 operated by the vacuum or suction created in said inlet manifold.

I also provide means for preventing the engine being started until the spark is retarded. Such means comprises a switch 17 85 on the timer which has its contacts 18 normally spaced apart, but said contacts being moved in engagement with each other when the timer head is moved to retard the spark 90 through means of a part 19 on the head engaging the plunger 20 of the switch. One of the contacts 18 is connected by a conductor 21 with the ignition switch S and the other contact 18 is connected by a conductor 22 95 with a switch part 23 in the casing 1 and which is in engagement with a switch part 24 on the member 3 when said member is in raised position. Of course, the switch part 24 is insulated from the member 3. A circuit 25 connects the switch part 24 to the 100

terminal of the contact 13 which is connected by a conductor 14 with the ignition switch. Thus it will be seen when the ignition switch is closed, current will flow through the conductor 14 and through the contact 13 and arm 12 to the magnets, as before described, and the current will also pass through the conductor 25 and the switch parts 23 and 24 to the coil, but as soon as the starter switch 10 is moved, this circuit through the parts 23 and 24 is broken. Thus the engine cannot be started until the spark control is moved to a position to retard the spark, when the switch 17 is closed, so that current can flow to the engine.

It is thought from the foregoing description that the advantages and novel features of the invention will be readily apparent.

It is to be understood that changes may 20 be made in the construction and in the combination and arrangement of the several parts, provided that such changes fall within the scope of the appended claims.

What I claim is:—

25 1. In combination with an internal combustion engine, its ignition switch and its starter switch, said starter switch including a movable contact, a spring actuated latch member located in the path of said movable contact for preventing closing of the starter switch, magnetic means for moving said latch member to permit closing movement of the starter switch, a circuit for said magnetic means under the control of the ignition switch, and means for breaking the circuit of the magnetic means when the engine begins to operate.

40 2. In combination with the ignition switch and starter switch of an internal combustion engine, the starter switch including a movable contact, a casing containing the starter switch, a hinged latch member in the casing, a spring for normally holding said hinged latch member under the movable contact of the starter switch to prevent closing 45 of the starter switch, magnetic means for moving the latch member from under the movable contact, a circuit for the magnetic means closed by the ignition switch and including a pair of switch parts normally engaged, and means for moving one switch part away from the other switch part by the suction created by the operation of the 50 engine.

55 3. In an internal combustion engine having an ignition switch, having a starter switch with a movable contact, and also having an inlet manifold, a casing containing 60 the starter switch, a pivoted latch member in the casing, a spring for normally holding said latch member under the movable contact to prevent closing of the starter switch, a magnet for moving the latch member from 65 under the movable contact, a circuit for the

magnet closed by the ignition switch and including a pair of switch parts normally closed, a pipe connected with the inlet manifold and extending into the casing, and a member on one of the switch parts located adjacent that end of the pipe which extends into the casing whereby the suction from the manifold will act on said last named member through the pipe to separate the switch parts.

In testimony whereof I affix my signature.
EDWIN J. POOLE.
